(57) **CLAIM**

The ornamental design for a glamping accommodation, as shown and described.

DESCRIPTION

FIG. 1 is a front perspective view of a glamping accommodation with a cover;

FIG. 2 is a front view thereof, with the doors shown in an open position;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a side perspective view of the glamping accommodation of FIGS. 1-7 with the cover removed;

FIG. 9 is a front view thereof, with the doors shown in an open position;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a top view of the inner structure thereof with the doors shown open and with the roof of FIG. 8 removed;

FIG. 16 is a top perspective view of the inner structure thereof with the doors closed; and,

FIG. 17 is an enlarged, partial top view of a corner of the inner structure thereof with the doors open.

The broken lines illustrate portion of the glamping accommodation which form no part of the claimed design. The dash line in FIG. 17 shows where the partial view is cut off and forms no part of the claimed design.

1 Claim, 17 Drawing Sheets
